UNITED STATES PATENT OFFICE.

LEWIS C. VAN RIVER, OF NEW YORK, N. Y.

ART OF TAKING AND PROJECTING MOTION-PICTURES IN COLORS.

1,130,221.

Specification of Letters Patent. Patented Mar. 2, 1915.

Application filed April 8, 1912. Serial No. 639,264.

To all whom it may concern:

Be it known that I, LEWIS C. VAN RIVER, a citizen of the United States, residing at New York city, in the county of New York and State of New York, have invented certain new and useful Improvements in the Art of Taking and Projecting Motion-Pictures in Colors, of which the following is a specification.

10 My invention relates to the art of taking and projecting motion pictures in colors.

One of the principal objects of the invention is to provide an improvement in this art whereby it is possible to obtain a closer approximation to the colors of the subject than is possible with the methods heretofore used.

20 More specifically, my object has been to provide a method by the employment of which it is feasible to photographically record on the film and subsequently present in the production three or more of the primary color components of the original subject.

The method which has met with the greatest success up to the present time is limited 25 to the use of two color components, and, as a result, has failed to reproduce the real colors and shades of the original subject with anything more than a rough approximation.

30 A further object of the invention is to improve upon the two color process by providing a better distribution of the color value areas on the film so that the film may be run through the machine at a lower rate of speed than has been possible heretofore.

35 A further object is to eliminate or minimize what is known as "color flicker" which results when a single color is strongly predominant in the subject.

40 The invention has for further objects to provide such other improvements in this art as will be hereinafter described and claimed.

45 Suitable means for carrying out the improved methods which I have invented is shown in the accompanying drawings, wherein,

50 Figure 1 is a diagrammatic representation of a camera; Fig. 2 as similar view of the projecting machine; Fig. 3 a view of a shutter which may be used in the camera and projecting machine. Fig. 4 a fragmentary view of a film showing one arrangement of the color records or areas; 55 Fig. 5 a view similar to Fig. 2 showing a modification; Fig. 6 shows a film with a

different arrangement of the color areas from that shown in Fig. 4; Fig. 7 shows the arrangement of the film and a corresponding color screen, and Figs. 8 and 9 show 60 films for use in a two color process in which the color value areas have respectively different arrangements.

Like characters of reference designate like parts in the several figures of the drawings. 65

In the method of producing colored motion pictures which up to the present time has proved most successful, the subject is photographed on what is known as a panchromatic film through a series of alternately red and green color screens so that the alternate pictures on the film are records of the respectively red and green color components of the subject. The negative film so produced is then developed and a positive film made therefrom. The positive film is run through a projecting machine which is provided with a shutter having transparent screens colored red and green. The movements of the film and the shutter are 80 timed so that the light projected through the records of the red component passes through the red screen of the shutter while the light projected through the records of the green component of the subject passes 85 through the green screens of the shutter.

This method has the obvious disadvantage of reproducing only two colors of the original and such tints and shades as can be made by the combination of such two colors. 90

It was attempted to work out a three color process along the same lines but it was found that with any practical rate of speed for the film the eye would not retain all of the color sensations long enough to compose 95 all three colors into an integral whole. The fact seems to be that the eye will retain sensations from certain of the colors longer than sensations from others. The persistency value of the spectrum colors increases 100

from red to violet, red having the lowest persistency value. That is to say, after the physical stimulus has ceased the eye will retain the red sensation for a certain length of time. It will retain the other primary 105 color sensations for longer periods, each color having its particular persistency value. My invention, by taking advantage of this fact, provides a method of producing colored motion pictures in accordance with which 110 the successive images are so colored that with reference to any given area of the illumina-

nated portion of the screen or composite projected image the color or colors having relatively low persistency value occur more frequently than the color or colors having a higher persistency value. In this way, without exceeding the speed at which it is practical to run the film through the projecting machine it is possible to reproduce all of the color components of the original subject.

On the other hand, if only two color components are reproduced the advantage is secured of decreasing the speed of the film. In the two color method which has been above described, it has been considered necessary to run the film at about double the speed of the ordinary black and white picture film. This of course is a disadvantage.

Referring to Figs. 1 to 4 inclusive, 10 designates the box of a camera, 11 the lenses and 12 a panchromatic film which is intermittently moved in the direction indicated by the arrow. 13 designates a shutter which rotates continuously between the film 12 and the lenses 11. The shutter has the opaque sectors 14 between which are arranged multicolor screens, the colors of which are disposed in concentric arcuate bands. In screen numbered 1 (Fig. 3) the outer band is blue, the intermediate band green, and the inner band red, the latter being as wide as the other two put together. These screens are, of course, transparent, that is, transparent respectively to blue, green and red light waves. The shutter rotates in the direction of the arrow. The black sectors shut off the light from the film during its intermittent movements. In screen numbered 2 the red band occupies the position of the green and blue bands in screen numbered 1. In screen numbered 3 the red band is in the same position as in screen numbered 1 but the position of the blue and green bands is reversed. In screen numbered 4 the red is in the same position as in screen numbered 2, the blue and green being reversed. The film which is produced by the arrangements above described has thereon a series of pictures of the subject, each picture being divided into what may be termed primary color areas which reproduce photographically a record of three primary color components as found in the portions of the subject corresponding to said areas respectively. Fig. 4 gives a diagram of such film. The pictures, that is, photographic representations of the subject in this arrangement may be divided in groups of four, each group being a repetition of the preceding group. The arrangement of the color areas in each of the four pictures of a group differ but it will be observed, first, that the red color areas occur in every picture in larger proportions than those of other colors and are distributed so that when any two successive pictures of the

group are superimposed or projected upon the same surface the red areas entirely cover the component surface of one picture, and second, that the green and blue-violet color areas are so distributed that if the four pictures of the group are superimposed, or projected, one upon the other the green and blue-violet color will each cover its entire area. A film so formed (or rather a positive made from a negative so formed) is run through a projecting machine, such, for example, as that shown in Fig. 2. 12 designates the film, 15 the source of light, 16 the condensers and 17 the objective lenses. A shutter 14 exactly like that used in taking the pictures is primed so that its screens numbered 1, 2, 3 and 4, coincide with the correspondingly numbered pictures on the films. The film is run through the machine at a sufficiently high rate of speed that the eye of the observer will retain the color sensation produced by projecting the color components from the color areas in the successive pictures in the manner shown, so that, let us say, the red color sensation from picture number 1 of group A is retained by the observer until picture number 3 of group A takes its place while the green and blue-violet color sensations from picture number 1 of group A are retained until picture number 1 of group B takes its place. As the red color sensation from picture number 3 of group A and the green and blue-violet sensations from picture number 1 of group A die out, they are replaced by color sensations derived from picture number 1 of group B, in which the distribution of color areas is just the same as in picture number 1 of group A and so on throughout any length of film desired. Of course the colors in the subject may change but the color areas do not. The eye will be able to accomplish this work of composition, even though the film is not run at any higher rate of speed than is done with the two color process because it has twice as many red sensations in a given period as it has sensations of blue and green. It is obvious that this same system might be carried out with a greater degree of refinement having reference to the relative persistency values of the different colors, if it were deemed advisable to do so.

In Fig. 5 I have indicated means for projecting images from a film of the charactered above described which differs from that shown in Fig. 2 by the substitution for the rotating shutter of a color band 18, the color sub-divisions of which correspond with the color areas of the film, which travels synchronously with the film. Obviously the same arrangement could be used for taking the picture.

In Figs. 6 and 7 I have shown a simpler arrangement of the color areas on the film, the latter being designated 19. The color

areas in this case are coincident with the successive photographic representations of the figures of the subject. Number 1 is red, number 2 green, number 3 red and number 5 4 blue. By this arrangement the red image and hence the red sensation is produced twice as often as the green or blue image. The color screen 20 (or rotary shutter as the case may be) is of course colored to 10 correspond. This arrangement meets the requirements of vision incident to the low persistency value of the red sensation equally as well as that shown in the preceding figures. However, it does not equalize the volume of light projected on the objective screen and may, with certain subjects, give rise to an inequality of light that may be termed "light flicker." For example, suppose that the color red strongly 15 predominates in the subject. It is obvious that with the film shown in Fig. 6 the red areas will be more transparent than the green and blue areas. As a result, the volume of light projected will vary intermittently 20 producing a pulsating effect which is trying to the eyes. This is entirely overcome by the arrangement shown in Fig. 4, in which the volume of light is approximately equal for each image, that is, each 25 representation of the entire subject, regardless of the color distribution of the subject.

In Fig. 8 I have shown a film 21 which records only two color components, namely, red and green. Each group of pictures A² 30 B², etc., contains two records of red and one of green. The advantage which this film has over the two color films now used is that it may be run at a slower rate of speed through the projecting machine.

40 In Fig. 9 I have shown a similar two color film but with the color areas so arranged as to eliminate possible light flicker. Picture-number 1 of group A³ has first a green area one-third the width of the picture, then a red area two-thirds covering the remaining 45 two-thirds of the picture. Number 2 has a green area in the middle with red areas on each side. Number 3 is like number 1 except that the red and green are reversed. 50 The arrangement is the same in groups B³ and throughout the length of the film.

It will be readily understood that other dispositions of the color areas on the film 55 might be devised different from those shown and also that the process might be carried out with apparatus unlike that which has been described above. For example, by the use of suitable apparatus the film might be passed through the projecting machine continuously instead of by intermittent movements. It is also obvious that the sub-division of the color areas may be changed in any desired manner. Also the advantage of dividing each photograph of the subject into 60 color areas is not limited to the particular

cases herein described in which the color areas reproducing one color of the subject or a given portion thereof occur more frequently than those reproducing another color. By the term "color areas" I do not mean that the films need be actually colored. In carrying out the preferred method above described, that is with the use of colored screens in the projecting machine, they will not need to be actually colored. They 70 will be simply black and white photographic records of the several color components of the subject. Other modifications will suggest themselves to those skilled in the art.

By the term "image" as used herein I 75 intend the single visible presentation or picture projected (whether on a screen or otherwise) from one of the series of photographs of the subject which the film or other transparency provides. The term "projection," when used in a substantive sense, signifies the area or space, on a screen for example, which the images projected from the series of photographs on the film occupy in 80 succession.

I do not claim herein broadly the division of each image into different color areas, as this method forms the subject-matter of an application Serial No. 765,083, filed May 2, 1913, this feature of my method being 95 claimed herein only in combination with the provision whereby the color or colors of low persistency value are made to occur more frequently than the color or colors of higher persistency value.

The film forms the subject matter of application Serial No. 730,527, filed Nov. 9, 1912.

I claim:

1. The method of producing motion pictures in colors, which consists in projecting from a single series of photographs of the subject a single series of differently colored images in which the color or colors having the lower persistency value occur in any given portion of the projection more frequently than the color or colors having higher persistency value.

2. The method of producing motion pictures in colors, which consists in projecting from a single series of photographs of the subject a single series of images colored red, green and blue, in which series the red occurs, in any given portion of the projection, more frequently than the blue or green.

3. The method of producing motion pictures in colors, which consists in projecting a series of images in which each image has differently colored areas arranged so that in any given portion of the projection a color having relatively low persistency value appears more frequently than a color or colors having higher persistency values.

4. The method of producing motion pictures in colors, which consists in projecting

a series of images in which each image has differently colored areas arranged so that in any given portion of the projection a color having relatively low persistency value appears more frequently than a color or colors having higher persistency values, the colors being so arranged that when a certain number of images have been projected each color has been produced in each portion of the projection.

5. The method of producing motion pictures in colors, which consists in projecting from a single series of photographs of the subject a single series of colored images containing red and another color or colors, in which series the red occurs, in any given portion of the projection, more frequently than the other color or colors.

6. The method of producing motion pictures in colors which consists in successively projecting a series of images in which each image has differently colored areas arranged so that in every portion of the projection the color or colors having the lower persistency value is or are repeated more frequently than the color or colors of higher persistency value, the color areas being so arranged in successive images that when a predetermined number of images has been projected each color has been produced in every portion of the projection.

7. The method of producing motion pictures in colors which consists in repeatedly photographing a subject through color filters which selectively record in different areas of each photograph different color components of portions of the subject corresponding to said areas respectively, in such order that a certain number of successive photographs will, in the aggregate, record the several selected color components of every portion of the subject and reproduce the entire subject in the areas recording a color component of relatively low persistency value more frequently than in the areas recording a color component of higher persistency value; and projecting images from said photographs through color filters corresponding to the color filters through which said photographs were taken.

8. The method of producing motion pictures in colors which consists in repeatedly

photographing a subject through color filters which selectively record in different areas of each photograph the red and another color component of portions of the subject corresponding to said areas respectively in such order that a certain number of successive photographs will, in the aggregate, record the selected color components of every portion of the subject and reproduce the entire subject in the areas recording the red component more frequently than in the areas recording the other color component; and projecting images from said photographs through color filters corresponding to the color filters through which said photographs were taken.

9. The method of producing motion pictures in colors which consists in repeatedly photographing a subject through color filters selectively recording several color components of the subject in a single series of photographs which reproduce the subject in the records of a color component of relatively low persistency value more frequently than in the records of a color component of higher persistency value; and projecting a single series of images from said photographs through color filters corresponding to the color filters through which said photographs were taken.

10. The method of producing motion pictures in colors which consists in repeatedly photographing a subject through color filters selectively recording red and another color component of the subject in a single series of photographs which reproduce the subject in the records of the red component more frequently than in the records of the other color component; and projecting a single series of images from said photographs through color filters corresponding to the color filters through which said photographs were taken.

11. A process of color cinematography in more than two colors, wherein color screens are interposed successively in single series and in such order that every alternate screen interposed is red.
